(57) **CLAIM**

The ornamental design for a device for carrying a tubular container, as shown and described.

DESCRIPTION

FIG. 1 is a perspective view of a first embodiment of an open device for carrying a tubular container;

FIG. 2 is a rear view thereof;

FIG. 3 is a front view thereof;

FIG. 4 is a left side view thereof;

FIG. 5 is a bottom view thereof; and

FIG. 6 is a top view thereof.

FIG. 7 is a perspective view of a second embodiment of an open device for carrying a tubular container;

FIG. 8 is a rear view thereof;

FIG. 9 is a front view thereof;

FIG. 10 is a left side view thereof;

FIG. 11 is a bottom view thereof; and,

FIG. 12 is a top view thereof.

The right side view substantially mirrors the left side view.
